POURING ATTACHMENT FOR A BOTTLE
OR THE LIKE

Charles R. Conry, 540 N. Prior Ave.,
St. Paul, Minn. 55104

Filed Oct. 28, 1968, Ser. No. 14,202

Term of patent 14 years

Int. Cl. D9—99

U.S. Cl. D9—277

FIG. 1

FIG. 2

FIG. 3

FIG. 4

FIG. 5

FIG. 1 is a perspective view of a pouring attachment for a bottle or the like showing my new design;

FIG. 2 is a top plan view;

FIG. 3 is a front elevational view;

FIG. 4 is a side elevational view; and

FIG. 5 is a rear elevational view thereof.

I claim:

The ornamental design for a pouring attachment for a bottle or the like, as shown.
